UNITED STATES PATENT OFFICE.

GASPARE MEZZATESTA, OF HAMPTON, VIRGINIA.

CARBURETER.

1,328,180.

Specification of Letters Patent. Patented Jan. 13, 1920.

Application filed May 6, 1918. Serial No. 232,800.

To all whom it may concern:

Be it known that I, GASPARE MEZZATESTA, a subject of the King of Italy, and a resident of Hampton, (Langley Field, Royal Italian Flying Corps,) in the county of Elizabeth City and State of Virginia, have invented a new and Improved Carbureter, of which the following is a full, clear, and exact description.

10 This invention relates to carbureters and has for an object the provision of an improved construction wherein the usual float now in common use has been eliminated while means have been provided which will 15 supply the proper amount of gasolene or other fuel as needed.

A further object of the invention is the provision of an improved carbureter especially adapted for use on airplanes and 20 arranged with means whereby the carbureter will supply gasolene or other fuel from the supply tank whether the same is above or below the carbureter.

A still further object of the invention is 25 to provide a construction wherein the parts will automatically adjust themselves to supply a uniform mixture at comparatively low and at high speed as well as a uniform mixture at different elevations.

30 A further object of the invention is to provide a carbureter which will work in all positions without fear of fire.

In the accompanying drawings:

Figure 1 is a longitudinal vertical section 35 through a carbureter embodying the invention, same being taken approximately on line 1-1 of Fig. 2.

Fig. 2 is a sectional view through Fig. 1 on line 2-2.

40 Fig. 3 is a detail top plan view of a priming member embodying certain features of the invention.

Fig. 4 is a sectional view through Fig. 5 on line 4-4.

45 Fig. 5 is a top plan view of a double carbureter embodying the invention shown in Fig. 1.

Fig. 6 is a bottom plan view on a reduced scale of the carbureter shown in Fig. 1.

50 Referring to the accompanying drawing by numerals, 1 indicates a supply pipe designed to be connected with a tank of gasolene or other suitable fuel designed to be carbureted and 2 indicates a throat which is 55 to be connected to the engine, said throat accommodating the usual butterfly valve 3.

This valve is operated by an arm 4 connected in any suitable manner with the valve, said arm having one or more projections 5 engaging a stop 6 extending from the throat member 2 whereby the movement of the valve 3 is limited to a full open or a full closed position. The throat member 2 is provided with an alined extension 7 hereinafter fully described, which alines with an extension 8 on the casing 9. The casing 9 alines with the throat member 2 and is connected therewith by any desired means.

Arranged in the casing 9 is a venturi or choker 10 positioned so that the smallest section of the passageway 11 is slightly below the top of the main gasolene discharge jet 12. The jet 12 is provided with a vertical bore 13 extending from the upper end downwardly as shown in Fig. 1, and merges into a restricted passageway 14 accommodating the end 15 of the needle valve 16, which needle valve may be formed integral with the hood or bell member 17. Extending upwardly from the bell member 17 is a pin 18 loosely fitting into a socket 19 in the guide 20. This socket is of sufficient length to allow for a sufficient upward movement of the needle valve 16 to produce a full valve opening whereupon it will prevent any further movement. A spring 21 surrounds the pin 18 and acts against stop 20 and against the top of bell 17 for continually tending to hold the needle valve 16 against its seat and consequently passageway 14 closed. The passageway 14 opens into what may be termed a feed chamber 22 which may discharge through the passageway 14 or through an auxiliary passageway 23. A removable jet 24 is positioned in the transverse bar 25, said removable jet having a passageway 26 extending therethrough. The transverse bar 25 is preferably formed integral with the skirt 27 of the casing 9, and not only accommodates the auxiliary jet 24, but is provided with a passageway 23 and with an inlet passageway 28 which receives gasolene or other fuel from pipe 1. The main gasolene jet 12 is also preferably formed integral with the cross-bar 25. It will, of course, be understood that the cross-bar 25 leaves an ample opening in the skirt 27 for the passage of air upwardly into the venturi 10 and thence into the throat member 2, and thence into the engine. A filtering device 29 is fitted around the base of the auxiliary jet 24 as shown in Fig. 1, said

filtering device being constructed in any suitable manner, as for instance a rather fine wire mesh, and of such a length as to extend from the auxiliary jet 24 to the top of the 5 plug 30 which is threaded into the tubular projection 31. It will be observed that the tubular projection 31 is formed with a sufficiently large bore to provide a space between the walls thereof and the filter 29 so that any 10 foreign matter in the gasoline may drop down into member 31 and thereby not interfere with the free flow of the gasoline.

When the engine is in operation the butterfly valve 3 is open and air will be 15 drawn in through the skirt 27 and caused to pass through the venturi or choker 10 whereupon same will strike the bell 17 which will be raised thereby, whereupon the valve 16 will be opened and a quantity of gasoline 20 drawn through passageway 14. This gasoline will mix with the air as it passes through the venturi 10 so that a proper explosive mixture will be provided. As the engine speeds up the flow of air through 25 the venturi or choker 10 will increase in speed and although the speed of the air is increased the proportion of volume between the gasoline and the air remains unaltered. This is due to the eddy current of air in 30 the recess under bell 17, though the bell 17 and associate parts will not be moved as they are already in their full open position. This eddy current is caused by the bell deflecting air so that there will be a flow of air toward 35 the jet 12 which will cause the flow of fuel to be in proportion to the volume of air passing the butterfly valve 3. This reverse flow of air will act on the incoming air in order to produce a proper balance between 40 the supply of air and the supply of fuel whereby the mixture is maintained substantially uniform. It will of course be noted that when the engine increases its speed the suction in the throat member 2 will be increased in proportion, and the speed of the 45 air and pressure thereof will increase and decrease with the speed of the motor. In order to produce a uniform mixture at all times the bell 17 is so positioned and shaped 50 as to form a recess above the jet 12 whereby as the speed of the air increases in the venturi or choker a certain amount of eddy current or back flow of air will be created so that the increase and decrease of the flow 55 of gasoline will be in proportion to the volume of air and not to the speed thereof.

The extension 7 is provided with a diagonally arranged passageway 32 which has one end above the valve 3 when said valve 60 is closed and the opposite end in communication with the chamber 33. This chamber is closed at the upper end by a screw or cap 34 having a socket 35 in which the pin 36 reciprocates. Pin 36 is provided with a 65 pointed end 37 at the bottom, so that it will

act as a needle valve, and a lug 38 rigidly secured thereto or formed integral therewith, said lug acting as a stop for the spring 39, which spring acts on the lug and on the cap 34 for resiliently holding the valve 70 37 upon its seat. A priming screw 40 is threaded into the extension 7, as shown particularly in Fig. 2, said priming screw having a flat extension 41 projecting below the stop 38, whereby when said screw is rotated 75 one edge of the flattened portion 41 will engage the stop 38 and raise pin 36 and the valve 37 from its seat, whereby when the engine is turned over in starting gasoline will be drawn through passageway 23, chamber 80 42, jet 43, chamber 44, passageway 45, bore 46, chamber 33 and passageway 32. The jet 43 is removable and is provided with a passageway 47 extending therethrough whereby a supply of gasoline may freely pass to 85 the chamber 33 and thence into the engine. The jets 24 and 43 are removable so that larger or smaller jets may be substituted according to the flow of fuel desired.

As shown in Fig. 2 an air inlet 48 is provided near the valve 37, said air inlet having a side passageway 49 the opening of which is regulated by the valve member 50. The valve member 50 is provided with a spring 51 having an extension pressing 90 against the lug 52 so as to lock the valve member in any adjusted position. It will be noted that the air entering through passageway 48 will become carbureted and the mixture will then be introduced into the 100 engine by the usual suction of the engine. The priming screw 40 is provided with a tilting handle or lever 53 which may be connected with an adjusting rod extending to any convenient point whereby this priming screw may be tilted under special circumstances, as for instance when the carburetor is used on an airplane and the airplane is at a high altitude. When the airplane is at a high altitude screw 40 is rotated 105 for part of a turn so as to raise the valve 37 and thereby produce a suction or partial vacuum in chamber 33 which in turn acts on the gasoline in passageway 23 and chamber 22. The opening of the valve 110 37 will result in a resistance to the passage of gasoline through jet 12 while not allowing the gasoline to pass through passageway 32 as the suction in jet 12 is superior to the suction in passageway 32 when the butterfly 115 valve is fully open. When the valve 37 is opened against the action of spring 39 while the butterfly valve 3 is open the suction of the engine will produce a suction and rarefaction in passageway 23. This rarefaction 120 in passageway 23 will act as a counter-suction to the suction acting on the valve 15 whereby the result will be a leaner mixture. The passageway 32, valve 37 and associate 125 parts are used as just described. In addition, 130

when the engine is being started lever 53 is rotated at the same time that the motor is turned over for starting. As soon as the motor starts lever 53 is moved back to its former position, and since valve 37 remains open by the suction of the engine the motor will start easily even in cold weather. It will of course be understood that valve 3 is not a perfectly tight fit and sufficient air passes around said 10 valve to mix with the air and gasoline in passageway 32 so as to provide a sufficient explosive mixture to keep the engine running slowly or running idle. When starting the engine the priming screw 40 is turned 15 as just described and the engine turned over. As valve 3 is gradually opened the motor picks up so that more and more air will be admitted until the suction in the casting 10 is sufficiently great to raise the valve 16 off its seat whereby gasoline will be supplied through jet 12. When this occurs the rarefaction in passageway 32 and the associate passageways will be reduced to such an extent as not to be capable of lifting any 20 gasoline. As soon as the motor is started the priming screw 40 is allowed to go back to its former position.

The use of springs 21 and 39 results in the closing of the gasoline passageway when the 30 engine stops whereby the danger of fire is eliminated when the engine stalls or backfires. In addition these parts are arranged so that the gasoline is drawn into the engine through the action of vacuum or suction, which will allow the carburetor to be used with desirable results on airplanes even when the gasoline supply tank is below the carburetor, as the suction will lift the gasoline as it may be needed.

40 In starting the engine when cold priming screw 40 is turned until valve 37 is opened and the engine is turned over, either by hand or any desired way. This will supply a quantity of air through the passageway 48 and a comparatively large quantity of gasoline, which acts in a certain sense as a priming, so that the engine will start immediately. As soon as the motor starts the priming screw 40 is moved back to its former position, but when lever 53 goes back to its former position the action of the turning motor will keep the valve 37 open. As the engine increases in speed the speed of the air through the venturi or choker 10 will of course increase, but the flow of gasoline will not be increased as the action of bell 17 will cause the incoming air to produce an eddy current at the discharge end of the jet 12 so as to keep the flow constant as the volume 55 of air is kept constant so that there will be a uniform mixture regardless of the speed of the engine. When the device is used on an airplane and the airplane has ascended to a high altitude the rarefaction of air is

such as to cause the mixture to be too rich, 65 and to make the mixture poorer member 40 is turned somewhat so that the rarefaction or suction provided by the engine will be communicated to passageway 23. This will reduce the amount of gasoline passing from 70 the jet 12 by reason of the retarding effect caused by a suction on the gasoline in passageway 23 which will balance to a limited extent the suction on valve 15. When using the carburetor on an airplane the supply 75 tank may be somewhat below or above the carburetor and yet properly supply gasoline by reason of the suction produced by the engine.

In Figs. 4 and 5 will be seen a double carburetor embodying the invention shown in Fig. 1, in which the shaft 54 connects the butterfly valves of both the carburetor sections 55 and 56 whereby they will be actuated together. In airplanes double carburetors, or two connected carburetors are now commonly used and by combining the structure shown in Fig. 1 into one complete combined or double carburetor as shown in Figs. 4 and 5 a simple effective structure is produced answering the requirements of the present day airplane. In this form of carburetor the operating levers 53 are connected by a bar 57 which may extend to any convenient point whereby the priming 95 screws 40 are simultaneously operated for each carburetor section.

What I claim is:

1. A carburetor comprising a casing having a skirt, and a bar extending transversely of the skirt, said bar having a fuel inlet and a feed chamber and provided with a main jet extending into the casing and with a downwardly extending tubular projection into which the inlet opens, an auxiliary jet 100 opening into the feed chamber and tubular projection, a filtering device secured to the auxiliary jet and extending into the tubular projection, a closure for the tubular projection, a spring pressed bell in the casing 105 above the main jet and carrying a needle valve working in said jet, and a butterfly valve in the casing.

2. A carburetor, comprising a casing having a choker and provided with a throat, a 115 skirt and a bar extending transversely of the skirt, said bar having a fuel inlet and a feed chamber and provided with a main jet extending into the casing slightly above the smallest section of the choker, an auxiliary jet in communication with the inlet, and projecting into the feed chamber, a spring pressed bell in the casing above the main jet and carrying a needle valve extending into said jet, and a butterfly valve in the 120 throat of the casing.

GASPAR MEZZATESTA.
